UNITED STATES PATENT OFFICE.

THEODORE ABBOTT, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,069, dated July 25, 1882.

Application filed June 16, 1882. Term of patent 14 years.

To all whom it may concern:

Be it known that I, THEODORE ABBOTT, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a heading, A, to which is attached a series of chenille pendants, B, ornamented by the following arrangement of colors in the threads of which they are composed, to wit: A portion, *b*—say about one-half of the length of the pendant—is made up of a series of stripes, belts, or bands, of two or more different colors, so arranged or distributed as to present a substantially-uniform general effect throughout the length of the portion *b*. The remaining portion, *b'*, is made up of a series of stripes, belts,

or bands which differ materially in appearance from the stripes of the portion *b*, such difference being effected either by the use of different colors or by making the stripes of different width, or both, the result of which is to present by the stripes of the portion *b'* the appearance or effect of a variegated border or frieze upon the fringe.

I claim—

A design for fringe, consisting of pendants which for a portion of their length are striped, banded, or belted in a uniform general series, and for the remainder of their length are striped, banded, and belted so as to present a distinctively-different appearance from the first-named portion, substantially as set forth.

THEODORE ABBOTT.
